TOY FLYING SAUCER OR THE LIKE

Rufus F. Steadman, Harker Heights, Tex.
(P.O. Box 23, Killen, Tex. 76541)

Filed Mar. 6, 1967, Ser. No. 6,092

Term of patent 14 years

(Cl. D34—15)

Fig. 1

Fig. 2

Fig. 3

FIGURE 1 is a perspective view of a toy flying saucer embodying my new design, looking toward the bottom thereof.

FIGURE 2 is a perspective view looking toward the top thereof, and

FIGURE 3 is a bottom plan view thereof.

I claim:

The ornamental design for a toy flying saucer or the like, substantially as shown.
